(57) **CLAIM**

The ornamental design for a cap having interior pocket and
audio earphones, as shown and described.

DESCRIPTION

FIG. 1 is a front perspective view of the cap having interior
pocket and audio earphones;

FIG. 2 is a cross-sectional view taken along line 2—2 of
FIG. 3;

FIG. 3 is a top plan view of FIG. 1;

FIG. 4 is a bottom plan view thereof;

FIG. 5 is a front elevational view thereof;

FIG. 6 is a rear elevational view thereof showing stitching
attaching the interior pocket;

FIG. 7 is a left side elevational view thereof; and,

FIG. 8 is a right side elevational view thereof.
